UNITED STATES PATENT OFFICE.

WILLIAM H. SCHUYLER, OF GRAND RAPIDS, MICHIGAN.

PRINTING PRESS.

Application filed September 15, 1927. Serial No. 219,574.

My invention relates to printing presses, and more particularly to a hand operated type of printing press which is particularly adapted for use in establishments where a relatively small number of sheets are to be printed each day, as for example, in a restaurant where a comparatively small number of menus are to be printed daily.

The principal object of my invention is to provide a relatively inexpensive printing press of the above described class which will be operable to produce sharp or clean cut prints with a minimum expenditure of time and labor.

Other objects of the invention are; to provide a hand operated printing press which will be serviceable as a proof press in a printing establishment; to provide a printing press particularly adapted to use linotype for the type element; to provide a press of simple construction which will be rugged and durable; to provide a press which will be easy to operate, and in general, to provide an improved printing press of the class described.

Further objects and advantages of the invention will be understood by reference to the following specification and accompanying drawings in which I have illustrated a printing press of the above described class.

In the drawings:

Fig. 1 is a plan showing the platen element of the press moved to one side to afford free access to the base and type element of the press.

Fig. 2 is a section on the line 2—2 of Fig. 1, but showing the platen element in its normal operative position overlying the base and type element.

Fig. 3 is a section on the line 3—3 of Fig. 2. Referring now to the drawings, my improved press comprises a base 10, a platen 11 reciprocably mounted in an arm or bracket 12 which is pivotally mounted on a post 13, the latter being fixedly mounted in a boss 14 which is formed integral with the base 10.

The base 10 is preferably formed of a relatively heavy casting having a finished top face 15 which is adapted to receive and support a type element 16. The type element may be of any suitable form and construction but preferably comprises a chase 17 which is adapted to receive a plurality of linotypes 18 provided with the characters it is desired to print on paper or other stock. The chase 17 is provided with a pair of set screws 19—20 which threadedly engage suitable apertures in one

end of the chase and serve to clamp the linotypes tightly in place in the chase. The chase is also provided with a pair of pins 21 and 22 which depend from its opposite ends and are adapted to enter suitable apertures such as indicated at 23 provided in the base 10 to thereby secure the chase in rigidly fixed position on the base.

As above noted, the boss 14 is made integral with the base 10 and is disposed at one side of the finished surface 15 of the base, and is suitably apertured at 24 to receive the lower end of the post 13 which is fixedly secured in the said aperture by any suitable means, for example, a set screw 25.

The arm 12 is pivotally mounted on the post 13, being provided with an aperture 26 which fits over the post and a spacing collar 27 is provided for maintaining the bracket 12 in the desired fixed position of vertical adjustment relative to the base. The bracket is also slotted as shown at 28 and a pin 29 projecting laterally from the post 13 enters the slot 28 to limit pivotal movement of the bracket about the post. It will be readily understood from an inspection of Fig. 1 that the platen 11 may be swung from its inoperative position as shown, to operative position over the base, as shown in Fig. 2, being limited in such movement by engagement of the end wall 30 of the slot 28 with the pin 29. Similarly the end wall 31 of the slot limits pivotal movement of the bracket and platen from operative to inoperative position as shown in Fig. 1. A collar 32 and nut 33 engaging a reduced and threaded end portion 34 of the post 13 serves to lock the bracket 12 on the post. It will be understood that the nut 33 is limited in its downward movement on the threaded portion 34 by engagement with the end shoulder 35 of the post and that by providing a collar 32 of proper width, any danger of binding the bracket against pivotal movement is overcome.

The platen 11 is mounted in the free end of the bracket 12 so as to be reciprocable in a vertical direction relative to the base, i. e., towards or from the base. For so mounting the platen I provide the free end of the bracket with an open-sided slot 36 which is adapted to slidably receive a flat bar 37. The bar 37 is provided at its upper end with an extension or stud 39, around which a coil spring 40 is disposed and compressed between a cap 41, which is secured to the upper end of the stud 39 by means of a screw

100

105

110

42, and the bottom wall 43 of a recess or counter bore 44 provided in the upper end of the free end of the bracket 12. It will be seen that the spring 40 normally urges the 5 bar 37 to move upwardly, such tendency being overcome when the top edge 45 of the bar is even or flush with the bottom 43 of the recess so that the pressure of the spring is taken up between the cap 41 and the said top 10 edge 45 instead of between the cap and bottom wall 43 of the recess. The lower end of the bar 37 is preferably provided with a relatively short extension or stud 46 which is adapted to enter a socket or recess 47 provided 15 in the boss 48, which is formed as an integral part of the platen 11. The stud 46 is preferably provided with a pair of recesses 49 and 50 for receiving the end portions of screws 51 and 52 respectively which threadably engage suitable apertures provided in the boss 48 and whereby the platen is adjustably connected to the bar 37. The recesses 49 and 50 are preferably of greater width or diameter than the corresponding dimension 20 of the respective screws 51 and 52, and the screws are turned inwardly sufficiently to retain the platen on the stud 46, but so as to permit a small degree of universal movement of the platen about the said stud 46. The 25 lower end 53 of the stud engages the bottom wall of the recess or socket 47 when the platen is moved downwardly into engagement with the type element so that the screws 51 and 52 are not required to withstand the pressure 30 applied to the platen during the printing operation.

Any suitable means may be provided for facilitating lowering of the platen against the pressure of the spring 40, and in the present instance I provide crank mechanism which includes a shaft 54 rotatably mounted in an aperture 55 provided in the bracket 12 and extending at least partially through the slot 36 as will be clearly understood from 45 an inspection of Fig. 2. The shaft 54 is provided with a crank pin 56 intermediate its ends which is aligned with the slot 36 so as to move therein when the shaft is rotated and the shaft is thus provided with spaced 50 bearing portions, as clearly shown in Fig. 3, which provide inwardly facing shoulders 57 and 58 which in effect form parts of the respective side walls of the slot 26. The bar 37 is provided with a notch 59 in its inner edge adapted to receive the crank pin 56 whereby rotation of the shaft 54 with corresponding movement of the crank pin will be effective to move the bar 37 in the slot 36. The shaft 54 is preferably provided with a 55 handle 60 for facilitating manual operation thereof, and as shown in Figs. 2 and 3, the crank pin is disposed in the upper portion of the shaft so that rotation thereof will be effective to lower the bar 36 and platen 60 against the pressure of the spring 40.

In assembling the mechanism above described, the shaft 54 is first inserted into the aperture 55 so as to align the crank pin portion 56 with the slot 36. The bar 37 is then inserted from the open side of the slot 36 so that the notch 59 embraces the crank pin, and a retaining plate 61 is then secured to the free end of the bracket 12 in any suitable manner as by means of screws 62 and 63 to lock the bar in operative position in the slot. 70 It will be noted that the bar then slides between the inwardly facing shoulders 57 and 58 of the shaft and thereby serves to prevent endwise displacement of the shaft.

The use and operation of my above described improved printing press is obviously very simple. It is only necessary to prepare a type element consisting of linotypes arranged in a chase as desired, and to mount the chase on the base of the press in relatively 80 fixed position by means of the pins 21 and 22. The type element is then inked in any desirable manner as for instance, by means of a small hand inking roller which may be rolled over the face of the linotypes when the 90 platen is swung to inoperative position as shown in Fig. 1.

A sheet of paper or other stock to be printed on may then be placed over the type element and the platen then swung from inoperative to operative position, and depressed to force the stock into printing engagement with the type element. The printed stock may then be lifted off and another sheet inserted in its place preparatory to taking another 100 impression. In some cases it may be necessary to ink the type element for each impression, and in some cases two or more impressions may be taken after each inking of the type. The platen may or may not be swung 105 to inoperative position between each impression, as best suits the convenience of the operator, it being necessary to swing the platen only when the type is to be inked by the use of the above-mentioned inking roller. 110

The bottom face of the platen is provided with a press blanket or cushion 64 of leather or other suitable material, which insures the production of sharp or clean cut prints and the universal movement connection between 115 the platen and bar 37 permits the platen to adjust itself so as to engage the type element with equal pressure over its entire surface. The press blanket may be secured to the platen in any suitable manner, as for instance, 120 by cementing. I have found that the height of linotypes is usually so accurate that the universal connection between the platen and sliding bar may well be dispensed with, and the same connected rigidly, in which case the 125 press blanket affords such alignment or adjustment as may be required.

Other means may be provided for mounting the platen so as to permit movement thereof from operative position overlying the base, 130

to inoperative position, and other changes in the form, construction and arrangement of parts may be made without departing from the spirit of the invention, the scope of which should be determined by reference to the following claims which should be construed as broadly as possible consistent with the state of the art.

I claim as my invention:

- 10 1. In a printing press of the class described, the combination of a base for receiving and supporting a type element, a platen for forcing stock to be printed on, into printing engagement with the type element, a bracket mounted on said base in fixed position of vertical adjustment relative to the base but so as to be movable horizontally relative thereto, and means for mounting said platen on said bracket so as to permit reciprocation of the platen towards or from the base for effecting said printing engagement, said means comprising a part vertically slidably mounted in the bracket and connected adjacent its lower end to said platen, and a manually operable rotatable member for effecting vertical sliding movement of said member.
- 15 2. In a printing press of the class described, the combination of a base for receiving and supporting a type element, a platen normally overlying said base and operable to force a sheet of stock to be printed on, into printing engagement with the type element, and means for mounting said platen so as to permit vertical reciprocating movement thereof towards and from the base and also sidewise movement thereof from its normal overlying position to an inoperative position for permitting free access to the base, said means comprising a post fixedly mounted relative to said base and adjacent one side thereof, an arm pivotally mounted on said post in fixed position of vertical adjustment relative to said base, said arm, when in operative position of pivotal adjustment, projecting inwardly over the base and having its inner end provided with a vertically extending guideway, a part slidably mounted in said guideway and provided with a recess, a crank member rotatably mounted in said arm and having an eccentric crank pin entering said recess for effecting sliding movement of said part when the crank member is rotated, and means for facilitating manual rotation of said crank.
- 20 3. In a printing press of the class described, the combination of a base for receiving and supporting a type element, a platen mounted so as to be reciprocable towards or from the base for forcing a sheet of stock to be printed on, into printing engagement with the type element, and means for so mounting said platen comprising a bracket member mounted on said base in fixed position of vertical adjustment relative to said base, normally disposed in operative position over said base but horizontally adjustable to inoperative posi-
- 25 tion alongside the base, a member slidably mounted in said bracket and adjustably connected adjacent its lower end to said platen, whereby the platen is adapted to adjust itself to exert uniform pressure against the base throughout the entire effective area of the former, spring means for normally retaining said slidably mounted member in its upper position of adjustment, and manually operable means for effecting downward sliding movement thereof.
- 30 4. In a printing press of the class described, the combination of a horizontally disposed base member for receiving and supporting a type element, a platen mounted so as to be vertically reciprocable relative to said base for forcing a sheet of stock to be printed on, into printing engagement with said type element, and means for so mounting said platen comprising a bracket connected to said base in fixed position of vertical adjustment relative thereto, said bracket being provided with an open-sided vertically extending slot, a shaft rotatably mounted in said arm extending transversely through said slot and provided with an eccentric crank pin intermediate its ends adapted to move in the slot when the shaft is rotated, a bar slidably mounted in said slot and provided with a notch in its inner edge portion embracing said crank pin, the latter being thereby rendered effective when the shaft is rotated to impart vertical sliding movement to the bar, a retaining plate for locking the bar in said slot, means connecting the lower end of said bar with said platen, spring means yieldingly holding said bar and platen in their upper position of vertical movement, and a handle connected with said shaft for facilitating manual rotation of the latter to thereby depress the platen.
- 35 5. In a printing press of the class described, the combination of a horizontally disposed base member for receiving and supporting a type element, a platen mounted so as to be vertically reciprocable relative to said base for forcing a sheet of stock to be printed on, into printing engagement with said type element, and means for so mounting said platen comprising a bracket connected to said base in fixed position of vertical adjustment relative thereto, said bracket having a portion disposed over said base provided with an open sided slot, a crank shaft having bearing portions adjacent its opposite ends and a crank pin of small diameter relative to the diameter of said bearing portions, and disposed intermediate the same, the ends of said bearing portions adjacent said crank pin forming inwardly facing shoulders at opposite ends of the crank pin, said crank shaft bearing portions being rotatably mounted in said bracket on opposite sides of said slot with the crank pin aligned with the slot so as to be rotatable therein, a bar slidably mount-

ed in said slot and provided with a notch in its inner edge portion embracing said crank pin so as to be movable thereby when the crank shaft is rotated, said bar fitting between said inwardly facing shoulders to thereby prevent endwise displacement of the crank shaft, a retaining plate secured to said bracket over the open side of the slot for locking the bar in operative position in the slot, 10 means connecting said bar and platen to

gether for imparting movement of the bar to the platen, yielding means normally holding said bar and platen in their respective upper positions of vertical movement, and a handle connected to said shaft for facilitating 15 manual rotation of the shaft for depressing the platen against the pressure of said yielding means.

WM. H. SCHUYLER.
